UNITED STATES PATENT OFFICE.

JOHN McNEIL AND CHARLES McNEIL, OF GLASGOW, SCOTLAND.

LIQUID TRAP FOR EVAPORATORS AND LIKE APPARATUS.

Application filed December 18, 1923. Serial No. 681,414.

To all whom it may concern:

Be it known that we, JOHN McNEIL and CHARLES McNEIL, both British subjects, and residents of Glasgow, Scotland, have invented certain new and useful Improvements in Liquid Traps for Evaporators and like Apparatus, of which the following is the specification.

The invention relates to priming preventers for evaporators and the like of a type in which a truncated conical shell receives at its larger and lower end the moisture laden vapour from the evaporator or other vessel and delivers it towards the outlet from its lesser upper end.

The invention has for its object to provide in a simple manner further surfaces and further more or less tortuous passages for the vapour so that its moisture may be the more effectively given up during its passage from inlet to outlet.

According to the invention there is superposed upon the truncated conical shell referred to a second like shell of greater mean diameter. The annular conical or conoidal space between the two shells is closed at its upper end by a plate which may very conveniently be integral with one or other of the shells. This closure, and the base 30 of the outer shell are preferably inclined to the horizontal. Both shells are enclosed within an outer casing which may conveniently be of hemispherical form. The annular space between the two shells is connected by a trunk with the outlet from the evaporator or the like, and the vapour, finding its way axially up the inner shell, passes thence to the space between the outer shell and the casing and from thence to the annular space between the shells and so to the outlet. The apparatus is designed so as to give to the vapor gradual changes

of direction, in order to induce therein a swirling motion. The centrifugal force set up by swirling tends to throw the more liquid (heavier) elements of the vapor against the outer walls. The liquid given up is collected upon the diaphragm supporting the inner shell, which diaphragm is preferably slightly inclined towards the usual trapped outlet, not shown.

An example of the improved apparatus is shown in sectional elevation on an accompanying sheet of drawings.

In this example the inner conical shell A surrounded by the superposed like shell B is formed in one piece with the diaphragm plate C upon which it is supported upon the upper end of the evaporator casing D while the closure E for the annular passage between the shells and the means of support for the outer shell B is formed in one piece with the latter.

The whole is enclosed in a hemispherical casing F through which passes the outlet trunk G. Arrows indicate the direction of flow of the vapour.

What we claim is:—

A liquid trap for evaporators having a diaphragm plate, an inner truncated conical shell with its base supported on said plate, and a like shell of greater mean diameter than the first named shell, in combination with a closure between the upper ends of the shells, said closure supporting the shell of greater mean diameter and forming an annular conoidal passage between the shell, a casing enclosing the whole and a trunk connecting the annular space with the outlet from the whole.

In testimony whereof we have signed our names to this specification.

JOHN McNEIL.

CHARLES McNEIL.
